UNITED STATES PATENT OFFICE.

CHARLES H. TOMLINSON, OF MANSFIELD, OHIO, ASSIGNOR TO THE TOMLINSON COUPLER COMPANY, OF MANSFIELD, OHIO, A CORPORATION OF OHIO.

CAR COUPLER.

Application filed January 31, 1924. Serial No. 689,786.

My invention relates to automatic car couplers for mechanically connected cars and is especially adapted for use on mine or industrial cars where it is not especially desired to couple the cars end about, but where the cars are usually positioned in a certain relation to each other and are maintained in that relation.

When it is desired to couple the cars end about it is then advisable to have couplers heads which are duplicates.

My invention resides in the new and novel construction and combination of the various parts hereinafter disclosed and set forth in the specification and claims and disclosed in the drawings accompanying this specification.

In the drawings:

Fig. 1 is a top plan view of two coupler heads in coupled relation.

Fig. 2 is a side view of Fig. 1.

Fig. 3 is a bottom view of Fig. 1.

Fig. 4 is a face view of the left hand half of the coupler shown in the previous figures.

Fig. 5 is a horizontal sectional view of Fig. 1.

Fig. 6 is a vertical view of Fig. 1 in partial section, showing the relation of the various parts and the locking cam for maintaining the parts in coupled relation.

Fig. 7 is a side view in partial section of two cooperating heads in partially coupled relation to show the manner in which the locking cam operates when the heads are being brought into coupled relation or when they are being parted.

In the preferred embodiment of my invention I employ two coupler heads A and B arranged to cooperate with each other and which are secured to the ends of the cars to be coupled by means of the ball member 1 which is secured to the tail piece 2, and which in turn has a projecting member 3 projecting therefrom and upon which are mounted in slidable relation thereto the members 4 and 5. The members 4 and 5 are held separated by means of the spring 6 interposed therebetween and are limited in their distance apart by the end of the member 2 and the head 7 of the member 3. A tail piece so constructed to yieldably connect a coupler head to a car is not new and the details of construction are not claimed herein.

As is well known to those skilled in the art, the member 1 is secured to the car bottom through the medium of what is known as an anchorage casting and which permits universal movement of the coupler head 60 with respect to the car. The coupling member A is provided with a hollow body member 8 and positioned within the hollow member 8 is a partition 9 against which the member 5 may butt, and the body member at its 65 extreme end is also provided with a collar 10 secured thereto by the through bolts 11. The collar 10 has a central passage through which extends the tail piece stem 2 in slide- 70 able relation. It is evident that if the member 1 is fixed to a car body and pressure is brought against the face end of the member 8 sufficient to cause it to yield, that the spring 6 will be compressed through the movement of the members 5 and 8 in a direc- 75 tion toward the anchorage casting, the member 4 being held against movement by the stem 2. It will also be evident that if the member 8 is moved away from the car to which it may be secured, that in that case 80 the members 4, 8 and 10 will move in a direction away from the anchorage casting thereby compressing the spring 6 since the member 5 is immovable.

The front end of the member 8 is provided with a rectangular recess 12 having an enlarged opening adapted to receive the projecting pin 13. While I have shown the recess 12 as rectangular it may be of other suitable shape. The side faces of the member A are each provided with an inwardly projecting flange 14 which form the boundary of the opening to the recess 12 and strengthen the sides. The lower edge of the member 8 and central thereof is cut away, 95 together with the adjacent portion of the body member 8 to form a recess or slot 15 in which is positioned the locking latch 16. Depending from the lower face of the body member 8 adjacent the lateral sides of the 100 slot 15 are hinge lugs 17 adapted to receive the hinge pin 18. Mounted upon the hinge pin 17 is the locking latch 19 provided with a collar portion 20 laterally pierced to receive the pin 18, and an operating member 105 21 projecting rearwardly therefrom and provided with lateral projecting members 22 which project beyond the side faces of the coupler and are adapted to receive either the hand or foot for rotating the locking 110

latch about its pin 8 in order to release the coupler head B from the coupler head A when desired. Secured to the member 21 and the body member 8 is a spring 23 for normally holding the locking latch in a locking position with respect to the coupler B. When the member 21 is rotated about the pin 18 by application of force to the member 22 the locking latch will be rotated about the member 18 as shown in Fig. 7, and the spring 23 will be placed under tension as long as the locking latch is held as shown in Fig. 7, put upon releasing the force applied to the member 22, the spring 23 will return the locking latch to its normal position shown in Fig. 6. The locking latch is also provided with a projecting locking lug 24 rigidly secured to the collar 20 and adapted to engage the coupling head B. The locking latch has its pivotal end so constructed that when the coupler pin 13 is moved into or out of coupling relation with the coupler head A the latch will permit the operation without interference and this is brought about by making the face 25 on the locking latch so that it will not extend into the path of the coupler head B when the coupler head B is being inserted or withdrawn. In Fig. 7 the surface 25 is shown as being flush with the inner lower surface 26 of the coupler head 8 and as shown, the pin 13 may be either advancing or retracting. If the coupler pins 13 is advancing into coupling relation with the coupler head A, the locking latch 19 is automatically rotated about the pin 18 from the position shown in Fig. 6 to that shown in Fig. 7. If the coupling pin 13 is being withdrawn from coupling relation with the coupling head A, the locking latch 18 must first be moved manually from the position shown in Fig. 6 to the position shown in Fig. 7.

The coupling head B has the same method of securing to the car as the coupling head A and also has the same buffering spring arrangement as the head A. The forward end of the coupler head B, however, is provided with the projecting pin 13. The sides 27 of the projecting pin 13 adjacent the inwardly projecting face flange 28 are spaced apart approximately the same distance as the flanges 14 and hence the projection has a width substantially that of the rectangular opening in the face of the cooperating coupler head. This construction provides that when the heads are in coupled relation they are held against relative lateral and vertical movement, and since the opening and pin are of irregular cross section, this will prevent also the heads rotating relative to each other. The portion of the pin 13 in advance of the straight portion is formed with vertical tapering sides 29 and the oblique tapering sides 30 by means of which the coupling heads A and B are guided into position when the

coupler heads are brought together. The upper and lower faces of the pin 13 are to a large extent flat and parallel and as I prefer to make the adjacent inner faces of the walls of the member 8 to correspond therewith and in close relation thereto, the front end of the pin 13 will be supported to a large degree by the inner walls of the member 8 while the rear end of the pin will be supported and held in position by the inner edge of the flange 14.

In the lower face of the pin 13 is a lateral slot 31, the surface of which is the arc of a circle having a radius the center of which is substantially the center of the pin 18 when the heads are in coupled position, also the face of the lug 24 which engages with the surface of the slot 31 is the arc of a circle whose radius is substantially equal to that of the slot 31 and the center of which is the center of the pin 18.

It will be evident that when two coupler heads A and B are brought into coupled relation that if the heads are not in perfect alinement longitudinally that the entrance of the point of the pin 13 within the opening 12 will bring the heads into alined relation. This will take place providing the heads are not too far out of alinement laterally. As soon as the heads are in a final coupled position they will be held there so far as lateral and rotatable relation are concerned through the relation of the pin 13 on the head B with respect to the openings within the member 8 of the head A. They will be held against longitudinal movement away from each other through the locking latch 19 engaging with the slot 31. As already explained the locking latch 19 will so operate when the heads are brought together that the coupling is made automatically if the heads are sufficiently alined that the pin 13 may enter the recess or opening 12. When the two heads are brought together with their faces in contact as shown in the various figures, the heads are held in this position through the engagement of the latch 19 with the groove 31.

By having the pin 13 of substantially full width of the opening to the recess 12 and the side walls 29 tapering to a point from full width, I find that such construction is superior to a pin of relative small cross section as compared with the opening as it permits the coupler heads coming together and alining when disposed at an angle to each other much more readily than with a relatively small pin, and the tapering side faces of the pin engaging the flanges 14 tend to move the heads into alinement for a greater angular displacement.

To uncouple the heads it is, of course, necessary to rotate the locking latch about the pin 18 which is done by applying force to the member 22 and pressing downwardly un-

til the latch assumes the position in Fig. 7 when the cars can be separated from each other.

There are, of course, modifications which may be made from the disclosure herein, but I do not wish to be limited other than by my claims.

I claim:

1. A car coupler comprising a pair of heads, means on each head to attach the head to a car, an abutting face on each head, an integrally formed projecting member on one head and having a rectangular cross section adjacent the face, the other head having an open recess of substantially full height and width of the head to receive the projecting member, the side faces of the projecting member converging toward each other and being tapered substantially their full projection from the abutting faces and cooperating with correspondingly tapered side faces of the recess opening to guide the heads laterally and to maintain the heads against lateral and angular displacement when in coupled position, and the other faces of the projecting member cooperating with the corresponding faces of the recess to maintain the heads in alinement and means to lock the heads in coupled relation.
2. A car coupler comprising a pair of cooperating heads of different construction, one head provided with a rectangular opening of substantially full width and height of the coupler face and surrounded by a narrow flat butting surface, the walls of the re-

cess comprising inwardly converging faces to be engaged by and to guide the cooperating coupler head and forming a flaring mouth the upper and lower faces of the recess back from the opening being parallel for a considerable distance while the side faces of the flaring mouth extend farther back into the recess than the upper and lower faces; the cooperating head having an integrally formed projection from its face and surrounded by a narrow flat butting face to engage the like face on the other coupler head, the projection being of substantially full width, adjacent the butting face, of the opening of the recess in the companion coupler and having converging side walls for substantially its full projection and shorter converging upper and lower faces adapted to engage the converging faces on the cooperating head to guide and aline the heads, the upper and lower faces of the projection back from the diverging faces being parallel for a considerable distance and adapted to cooperate with the parallel faces on the cooperating head to prevent relative vertical and rotatable movement of the heads, a slot in one face of the projection, a spring-held latch on the other head to engage the slot to hold the heads against relative longitudinal movement in one direction and arranged to be automatically moved when the heads are brought together.

In testimony whereof I affix my signature.

CHARLES H. TOMLINSON.
